UNITED STATES PATENT OFFICE.

ANNA KENDALL, OF ST. LOUIS, MISSOURI.

SOAP FOR RESTORING COLOR TO PLUSHES, VELVETS, &c.

SPECIFICATION forming part of Letters Patent No. 319,097, dated June 2, 1885.

Application filed April 3, 1885. (No specimens.)

To all whom it may concern:

Be it known that I, ANNA KENDALL, a citizen of the United States, residing at St. Louis, State of Missouri, have invented certain new and useful Improvements in Soap for Restoring Color to Plushes, Velvets, &c.; and I do declare the following to be a full, clear, and exact description of the invention, such as will enable others skilled in the art to which it appertains to make and use the same.

This invention relates to a soap which is used not only for cleansing, but also for restoring color to plushes, velvets, and like goods.

Prior to my invention various detergents have been compounded and designed for the same purpose as mine. The objection to the use of these has been that they are in a soft or fluid condition and liable to spill over and mess the goods.

My invention produces an article which is solid, conveniently handled, cannot be accidentally applied, and when applied only the desired amount is used.

To compound this article I take four pounds good quality of hard soap and dissolve it over a fire. It is then ready for the coloring. This depends upon the color desired. For one kind of soap I mix a sufficient quantity of ninety-five per cent. alcohol with four ounces of fuchsin crimson, thoroughly dissolving the latter, and then add this to the melted soap. To this add one-fourth ounce ammonia and one-fourth ounce sal-soda. Mix thoroughly while hot and pour into molds or vessel for cooling. After cooling it is in a hard or solidified condition, and can be handled like ordinary cake soap.

To make green soap, four ounces of Victoria green are used instead of crimson, the same process being used.

To make blue soap, blue aniline is used, same quantity; for purple soap, two ounces

blue aniline and two ounces fuchsin crimson; for yellow soap, four ounces yellow aniline; for brown soap, four ounces Bismarck brown.

Thus is produced a colored soap which is applied to the goods by the hand, which not only cleanses the goods, but also restores the color which has been lost by wear or light.

Of course, I do not confine myself to the precise proportions set forth, as they may be varied.

This soap is applied to car-seats and the like without removing the cover.

I am aware that it is not new to add coloring-matter to a saponaceous compound for the purpose of restoring color to goods, such being fully set forth in United States Patent No. 294,727; but my invention consists in making the soap in such a condition that its use is facilitated, and that it can be employed without waste or liability of smearing or messing the article to be renovated.

Having described my invention, what I claim is—

1. As an improvement in detergents for restoring color, soap in a solidified form containing a coloring-matter which is imparted to the article to be cleansed when the soap is applied, as set forth.

2. A detergent for restoring color, consisting of soap, coloring-matter, ammonia, and sal-soda, in about the proportions stated and in a solidified form, as set forth.

In testimony whereof I affix my signature in presence of two witnesses.

ANNA ^{her} X KENDALL.
mark.
